Charles Howard

UNITED STATES PATENT OFFICE.

CHARLES HOWARD, OF MORRIS, NEW YORK.

IMPROVED WASHING-MACHINE.

Specification forming part of Letters Patent No. **35,682**, dated June 24, 1862.

To all whom it may concern:

Be it known that I, CHARLES HOWARD, of the town of Morris, county of Otsego, and State of New York, have invented a new and useful Improvement on a Machine for Washing Clothes; and I do hereby declare that the following is a full, clear, and exact description of the construction and operation of the same, reference being had to the annexed drawing, making a part of this specification, in which the figure is a perspective view.

A is the trough. B B are disks or rubbers. C is a shaft. D D are arms. E is a handle. F F are the pitmen. H is the treadle. I I are shafts fastened to the disks. J is a pulley. A corresponding one is on the opposite end of the trough. (Not seen in the drawing.) K K are spiral springs surrounding the shafts I I. O O are cords attached to the shafts I I and to the treadle H, to spread the disks apart. S S are bearings fitted across the trough A, to hold the shafts I I and disks in their places in the trough. L L are posts to support the shaft C.

To enable others skilled in the art to make and use my invention and improvement, I will proceed to describe its construction and operation.

I construct the trough A of any desired size, in the shape of a half-cylinder, with suitable legs on the ends to raise it a convenient distance from the floor and to hold the ends of the treadle H.

The disks B B are made in a half-circle to correspond with the inside of the trough A, and are corrugated on their face sides and fastened to the shafts I I. The two posts L L are fastened to the ends of the trough A, and are of the proper height to support the shaft C and give sufficient length to the pitmen F F.

The shaft C is made of the desired length, with bearings at the ends to rest on the posts L L, and the arms D D are securely fastened to the shaft C on opposite sides at the proper distance from the ends to receive the pitmen F F, which (pitmen) are also attached to the disks B B. Put the spiral springs on the shafts I I and fit shafts and disks in the trough A, so that when the disks are spread apart the ends of the shafts I I will slip through holes in the ends of the trough.

Having fitted the shaft C, with its arms D D and handle E, in its place, proceed to attach the pitmen to the ends of the arms D D and to the disks B B on the same end—that is, the ends of the pitmen F F are connected to the edge of the disks both on the same side. Attach a cord to the shafts I I near the supports S S. Run the ends out through a hole in the end of the trough A, over a pulley, J, and fasten them to the treadle H.

To operate the machine, make a soapsuds and put in the trough A; put your foot on the treadle H and spread the disks apart; put the articles to be washed between the disks B B and take the foot off the treadle; seize the handle and move it back and forth or up and down until the desired result is obtained.

What I claim as my invention and improvement, and for which I desire Letters Patent, is—

The combination of disks B B on separate shafts, connected to the arms D D by means of the pitmen F F, whereby both disks are moved in opposite directions by one motion of the hand operating on the handle E, as described.

CHARLES HOWARD.
